UNITED STATES PATENT OFFICE.

ARTHUR O. WEBER, OF EUCLID HEIGHTS, OHIO.

COMBINED RESERVE FUEL CONTROL AND LOCK FOR AUTOMOBILES.

Application filed May 15, 1922. Serial No. 561,147.

To all whom it may concern:

Be it known that I, ARTHUR O. WEBER, a citizen of the United States, residing at Euclid Heights, in the county of Cuyahoga and State of Ohio, have invented a certain new and useful Improvement in Combined Reserve Fuel Controls and Locks for Automobiles, of which the following is a full, clear, and exact description, reference being had to the accompanying drawings.

This invention relates to devices used in connection with the operation of internal combustion engines, and is particularly concerned with the provision of mechanism for maintaining and indicating a reserve supply in a fuel tank.

One of the objects of my invention is to provide a valve mechanism which permits the flow of fuel from a supply tank until only a predetermined quantity remains in the tank and may be then operated for enabling the reserve supply to be used. An advantage of this arrangement is that the driver is effectively forewarned of the low fuel supply, before the actual supply is exhausted.

Another object is the provision of a mechanism which may be readily attached to existing fuel supply systems and to provide a valve mechanism which must be reset to operative position before the supply tank cover can be removed for filling purposes.

Other objects include the arrangement of manually operable elements and valve mechanism so that the valve may be closed and locked, thus cutting off the fuel supply, and providing an additional locking means to prevent surreptitious driving of the motor vehicle.

The means for carrying out my invention will be fully set forth in the following description, which pertains to the accompanying drawings, and the essential features will be summarized in the claims.

In the drawings, Fig. 1 is a diagrammatic section through a portion of a motor vehicle showing a supply tank and fuel conduit having a device constructed in accordance with my invention attached thereto; Fig. 2 is a plan view of the portion of the motor vehicle shown in Fig. 1 and showing one position of the valve operating lever used with my invention; Fig. 3 is a similar fragmentary view showing another position of the valve control lever; Fig. 4 is a plan view of the lever removed from the motor vehicle and

showing the locked position; Fig. 5 is a section on an enlarged scale and through the device embodying my invention; Fig. 6, 7, 8 and 9 are sections through the valve mechanism indicating various positions of the valve stem; Fig. 10 is an end view of the supporting bracket and segment; and Fig. 11 is a section taken through the supporting bracket shown in Fig. 9.

Designating the parts shown in the drawings by the use of reference characters, 10 indicates a fuel tank, 11 a sediment basin, and 12 a supply conduit for a fuel system used on motor vehicles. The supply tank 70 is shown as mounted beneath the front seat 13 and above the floor boards 14, as shown in Fig. 1. My invention is adapted to be placed in the supply line intermediate the tank and engine, and broadly embodies two 75 conduits leading from the tank, at different levels, to a common discharge line with valve mechanism associated therewith for controlling the flow, through either conduit as desired. In the embodiment shown, however, 80 one of these conduits is illustrated as a bypass.

In connecting the bypass to the main line, I prefer to employ a single piece structure, having a straight passageway 15 extending therethrough, and having a bypass passageway 16, which merges with the straight passage adjacent the end which is adapted to be connected to the sediment basin, as at 17. The end adjacent the junction of the main and bypass passageways, as at 18, is adapted to receive a flanged member 19 attached to the supply conduit 12. The bypass is shown as a U-shaped conduit, the top of which extends above the bottom of the supply tank. The end of the bypass remote from the tank is shown as merging with a passageway 20 which is disposed above the passageway 15, and which is arranged to be placed in communication with 95 main supply conduit by a valve 25.

The valve 25 is designed to permit the passage of fuel through either of the passageways 15 or 16, or to prevent the flow of fuel through either. Accordingly, in Figs. 6 to 9, the valve is shown as having a centrally disposed opening 26 with laterally disposed ports extending therefrom in such manner, as to register with the passageways 15 and 20, or supply conduit 12, as desired.

The port for providing communication with the passageway 20 is indicated at 27

adjacent the upper end of the opening 26, while those disposed adjacent the lower passageways are indicated at 28 and 29, respectively.

5 When the valve is turned to the position shown in Figs. 6 and 17, then the passageway 20 is open and the passageway 15 is closed. Thus fuel is caused to flow through the bypass 16 passage 20, port 27, opening 10 26, port 29 and then into the supply conduit 12. A vent 30 extending upwardly from the top of the bypass to a point adjacent the top allows the liquid to flow through the bypass until it reaches a point where the 15 seal is broken, as at 31, in Fig. 5.

To permit the passage of fuel through the main passageway 15, the valve is turned to the position indicated in Fig. 9 wherein the port 28 is in registration with the passageway 15 and the port 27 is out of registration with the passageway 20. This permits the remaining fuel in the tank to flow into the fuel conduit when the valve is turned to the position shown in Fig. 8, both the ports 25 27 and 28 are out of registration with their respective passageways, and hence the supply is stopped.

To turn the valve to the various positions, indicated in Figs. 6 to 9, I have shown a 30 valve stem 35 which extends upwardly from the valve and terminates, as shown in Fig. 11, adjacent an arm 36 to which it may be rigidly attached. This arm is adapted to be supported in a bracket 37 which in turn 35 may be attached to a vehicle body, as shown in Fig. 1. The bracket is illustrated in Fig. 4 as having a segment 38 projecting laterally therefrom and as having an opening 39 which is adapted to register with a 40 corresponding opening 40 in the arm 36, and operating lever 41, whereby the valve may be locked in closed position. The lever 41 may comprise an extension of the arm 36, but I have shown it 45 as a separate member rigidly attached to the arm and provided with an extension piece 42, which projects over the cover 43 of the fuel tank.

In normal running position, that is, when 50 the fuel flows through the bypass 16, the position of the extension 42, as shown in Fig. 2, is such as to permit the cover 43 to be removed. Then when the fuel has been used to such an extent that it is necessary to use 55 the reserve supply the valve is shifted to cause the flow of fuel through the main passageway 15. To move the valve to this position, it is necessary to raise the seat 18 and to insert a tool, such as a screw driver, into 60 a slot 44, thus drawing the extension across the cover. This is accomplished through the usual hand opening 45 in the plate beneath the seat. Suitable characters, as indicated in Fig. 3, by the word "Empty" 65 may be placed on the extension piece so as to

be brought into view when the valve mechanism is operated to use the reserve fuel supply.

To lock the valve in closed position, as indicated in Figs. 4 and 8, the plate beneath 70 the seat is raised, and the hand lever is shifted until the opening 40 is brought into registration with the opening 39 on the segment, whereupon the two members may be locked by a pad lock, or by any suitable 75 fastening means.

The operation of the device constructed in accordance with my invention is as follows:—

Assuming that fuel is in the tank 10 and 80 that the bypass is connected to the supply line, then the valve operating lever is placed in the position indicated in Fig. 2, thus bringing the port 27 into registration with the passageway 20 and causing fuel to flow 85 through the bypass 16. The engine then operates on fuel flowing through the bypass until the level within the supply tank drops to a point where the seal at the top of the bypass is broken. The operator is warned 90 of this condition, obviously by stoppage of the engine. Then the lever 41 is moved to the position indicated in Fig. 3 whereupon the port 27 is moved out of registration 95 with the passageway 20, and the port 28 is brought into registration with the passageway 15, thus causing fuel to flow through the main passageway and into the supply conduit 12.

When the operating lever is moved to this last mentioned position the warning characters on the extension piece serve to indicate the necessity for more fuel. Before the tank is filled, however, it is necessary to turn the lever 41 back to the position indicated in Fig. 2, thus insuring a turning of the valve to bring the port 27 into registration with the passageway 15, so that the device is automatically reset when the tank is refilled. If desired, the lever 110 100 may be moved to the position indicated in Fig. 4 and locked to the bracket, thus preventing the flow of fuel through either the main passageway 15 or bypass 16.

In view of the foregoing description, it 115 will be seen that my invention provides an automatic indicator which positively maintains a reserve fuel supply, and which must be reset to the operative position before additional fuel can be inserted in the supply tank. In addition, the device may be readily attached to existing motor vehicles without necessitating extensive changes in the fuel line. A further advantage is that 120 a positive lock may be obtained against the removal of fuel from the supply tank whenever desired.

Having thus described my invention, I claim:—

1. In combination, a fuel supply tank, a 130

- device having a main conduit and a bypass conduit therein, means for connecting the device to the tank below the bottom of the tank, the bypass conduit extending parallel to the main conduit adjacent one end of the device, and a valve having a central passageway with lateral passageways extending radially therefrom adapted to communicate with the respective parallel conduits, and means whereby the valve may be operated to control the flow of fuel. 25
- 5 2. In combination, a fuel supply tank having an outlet in the bottom thereof, and having an inlet opening in the top, a closure for the inlet, a sediment basin connected with the outlet and having a laterally extending passageway, a device having a main conduit and a bypass conduit, a valve carried by the device at the junction of the main and bypass conduits, the other end of the device being connected to the passageway in the sediment basin, a valve stem extending upwardly from the valve and projecting above the top of the tank, and means associ- 30
- 10 ated with the stem for preventing the removal of the closure when the valve stem is in a predetermined position. 35
- 15 3. In combination, a fuel supply tank having an opening therein, a sediment basin connected thereto, a self-contained device attached to said basin and having a main conduit and a bypass conduit, the bypass conduit projecting above the bottom of the tank and extending parallel to the main conduit adjacent the end of the device remote from the basin, a valve extending transversely of the conduits and arranged to control the passage of fuel through either of said conduits, a valve stem projecting above the tank, a shield having a width sufficient to entirely cover said closure 40 whereby access to the closure is prevented until the valve stem is moved to predetermined position. 45

In testimony whereof, I hereunto affix my signature.

ARTHUR O. WEBER.
